TABLECLOTH

Richard A. Fees, Ardsley, Pa., assignor to Quaker
Lace Company, Philadelphia, Pa.

Filed June 7, 1961, Ser. No. 65,499

Term of patent 3½ years

(Cl. D92—26)

The figure is a plan view of slightly more than quarter section of the tablecloth showing my new design, the other three sections being identical with the section here disclosed, arranged in proper relation to complete the tablecloth. The section disclosed is shown over a dark background to bring out the details of the design.

I claim:

The ornamental design for a tablecloth, substantially as shown and described.
